UNITED STATES PATENT OFFICE.

JOHN A. KEANE, OF NEW YORK, N. Y.

DESIGN FOR A BRUSH-HOLDER.

SPECIFICATION forming part of Design No. 32,012, dated December 19, 1899.

Application filed November 17, 1899. Serial No. 737,374. Term of patent 14 years.

To all whom it may concern:

Be it known that I, JOHN A. KEANE, a citizen of the United States, residing at New York city, in the county of New York and State of New York, have invented and produced a new and original Design for Brush-Holders; and I do hereby declare the following to be a full, clear, and exact description of the same, reference being had to the accompanying drawing, forming a part thereof.

The figure of the drawing represents a perspective view of a brush-holder, showing my new design.

As shown in the drawing, the leading or material feature of my design consists of an open oval frame having a series of points or

teeth on the bars thereof and an arm extending downward and outward therefrom, said arm provided with a point or prong. This oval frame is mounted upon the end of a spirally-corrugated post, as shown in the drawing.

Having thus fully described my new design, what I claim as my invention is—

The design for a brush-holder, as herein shown and described.

In testimony whereof I affix my signature in presence of two witnesses.

JOHN A. KEANE.

Witnesses:

PAUL G. KEANE,
WILLIAM H. SCHILLING.
